FISH SCALER

Lloyd G. Burns, 1461 Camille St.,
Shreveport, La. 71108

Filed Jan. 18, 1971, Ser. No. 107,602

Term of patent 14 years

Int. Cl. D15—08

U.S. Cl. D55—1 E

FIG. 1

FIG. 2

FIG. 3

FIG. 4

FIG. 5

FIG. 6

FIG. 7

FIG. 1 is a front perspective view of a fish scaler showing my new design with the front doors in an open position;

FIG. 2 is a front elevation view of a fish scaler showing my new design with the front doors in a closed position;

FIG. 3 is a side view of a fish scaler showing my new design;

FIG. 4 is a top view of a fish scaler showing my new design;

FIG. 5 is a front perspective view of a fish scaler showing my new design with the front cabinet doors and the inner mesh basket door in open positions;

FIG. 6 is a front elevation view of a fish scaler embodying my new design with the front cabinet doors and the inner mesh basket door in open positions; and

FIG. 7 is a side view of my new design for a fish scaler showing the front cabinet doors and the inner mesh basket door in opened positions.

The rear of my fish scaler is rectangular and plain.

I claim:

The ornamental design for a fish scaler, as shown and described.
